COIN SEPARATOR

John Gottfried and Benjamin Fry, St. Louis, Mo.

Application February 28, 1947, Serial No. 731,558

4 Claims. (Cl. 194—97)

1

This invention in general relates to coin apparatus and more particularly to a new device for separating from acceptable coins all coins having abnormal surface deformations, improper diameters and under weight, and including means for scavenging and clearing the device when blocked by rejected coins.

In coin testing devices previous to this invention, independent means were employed for testing coins for surface deformation from the usual means employed for testing weight and size. These independent structures were not only more expensive to manufacture and service, but were sensitive to position and inefficient in operation because of the lack of precise coordinated timing in their operation resulting from the necessity for testing coins traveling at different velocities.

The present invention overcomes the above objections through the provision of a single combination of elements for simultaneously and concurrently acting upon each coin propelled by gravity and effectively testing them for size, weight and surface deformation. This feature inherently provides a troublefree structure which lends itself to low cost manufacture, effective operation, and relatively insensitive to position.

The principal object of the invention is the provision of a gravity-operated rejection means for testing the surface of a coin pivotally secured to a gravity restored rocker for testing the weight and diameter of the coin during the descent of a gravity-propelled coin in a passageway.

A further object of the invention is a combination of elements comprising a gravity restored pivotal means for testing for surface deformation, including means for scavenging rejected coins suspended therein.

These and other objects and advantages will appear in one embodiment of the invention described and shown in the following specification and drawings in which:

Fig. 1 is a side-elevation of a conventional coin separator showing the invention applied to its entrance passageway.

Fig. 2 is a cross-sectional plan view of the device shown Fig. 1 taken generally through section line 2—2.

Fig. 3 is a fragmentary view of a portion of the device shown Fig. 1 in changed position.

Fig. 4 is a fragmentary cross-sectional plan view of the device taken through section line 4—4 Fig. 3.

2

Fig. 5 is the same as Fig. 4 in changed position.

The testing apparatus hereinafter described is shown positioned in the entrance passageway of a well-known type of slug rejector which incorporates magnetic and other means for subsequent testing, and it will be understood that the invention is applicable in any type of coin passageway for rejecting coins of improper dimension, weight and shape.

Referring to Figs. 1, 3 and 4, the plate 1 is a frame or housing for the entire device. A gate member 2 is pivotally secured to plate 1 by ears 3—3 and 4—4 projecting from the frame and gate respectively and having a hinging pin 5 therethrough. A coil spring 6 positioned around pin 5, having its opposite ends bearing against the plate 1 and gate 2 respectively, normally urges the gate 2 into normal proximity with the plate 1 as shown in Fig. 2.

An abutment pin 7 in gate 2 normally bears against the inside surface of plate 1 to establish proper spaced relation between plate 1 and gate 2 forming an entrance passageway 8 shown Figs. 2 and 3. A runway 9 secured to the inside surface of the gate, provides a sloping acceptance passageway running between the magnets 10—10 wherein coins are tested for their conductivity properties and thence to other test means not shown. Rejected coins are directed downward as shown by dotted arrow directly beneath the entrance passageway 8 Fig. 1, into rejection hopper 11 and thence to a rejection passageway not shown.

A cradle or rocker 12 is pivotally secured adjacent to the outside surface of the gate 2 on pivot 13 integral with gate 2. The rocker is provided with two spaced projections 14 and 15 extending through clearance apertures 16 and 17 in the gate. The rocker is normally urged in the position shown Fig. 1 by its weighted portion 18 with the projections 14 and 15 extending into the entrance passageway. The distance between projections 14 and 15 is proportioned to permit the free passage of undersized coins therethrough to momentarily straddle and retain a coin of proper diameter.

A crank shaped feeler lever 19 is pivotally secured for movement in a retainer plate 20 which plate is adjustably positioned on rocker 12 about pivot 13 by screw 21. One end of lever 19 terminates in an offset integral counterweight 22 and its opposite end terminates in an offset feeler projection 23. When the rocker 12 is in rest position as shown Figs. 1 and 2, the action of gravity

upon counterweight 22 normally urges the projection 23 against a camming edge 24 of gate 2.

A pusher bracket 25 loosely positioned on gate 2 by a pair of projections 26, extending through mating holes 27, normally rests against a stud 28 in plate 1 Fig. 2, and is urged in this position by contact with a formed flat spring 29 held to gate 2 by rivet 30. A tongue 31 formed in the end of bracket 25 normally extends into aperture 16 and is adapted for movement through aperture 16 of the gate 2 between rocker projections 14 and 15.

A retainer plate 20 and its feeler lever 19 is adjustably mounted on cradle 12 so when in rest position the end of the feeler projection 23 just clears a coin as it first comes in contact with the cradle projections 14 and 15.

In operation and assuming that a coin of proper weight and diameter is deposited in the entrance passageway 8, Fig. 1, the coin will impinge upon and straddle rocker projections 14 and 15 and overcome the force exerted by the counterweighted portion 18 of the rocker 12 and thus cause the rocker to rotate in a clockwise direction. When the rocker has rotated sufficiently to relieve the engagement of camming edge 24 from the projection 23, the force of gravity acting upon counterweight 22 will cause the feeler lever 19 to rotate and move its projection 23 with its end in frictional contact with the face of the coin, and assuming the coin has a proper, smooth surface, the coin will continue movement in the rocker until it is deposited on the coin runway 9 as illustrated by Fig. 4, where it will descend between the magnets 10 for test and thence continue its descent for further tests by means not shown.

When a coin is deposited in entrance passageway 8 having proper diameter and sufficient weight to normally operate the rocker, but having a hole or other abnormal deformation in its surface, it will impinge upon projections 14 and 15 and operate the rocker 12 in a normal manner which will cause the feeler lever to move its projection 23 in a direction substantially normal to the surface of the coin and thus engage a hole or other abnormal deformation therein, and suspending the coin in the entrance passageway on projection 23, as illustrated in Fig. 3. Under these conditions the gate 2 is moved outwardly from the inside surface of the plate 1 against the restraining action of spring 6 by well known means not shown, and as illustrated in Fig. 5. Since the movement of the gate 2 in an outward direction will permit the bracket 25 under the influence of spring 29 to move inwardly with respect to the movement of the gate, the coin suspended by feeler projection 23 will be stripped therefrom by tongue 31 whereby the coin will fall by gravity directly into the rejection hopper 11. It is apparent that a coin of insufficient weight, having a proper diameter, will not rotate the rocker 12 sufficiently far to discharge it on to the runway 9 and will require the same scavenging movement of gate 2 as previously described, to discharge the underweight coin into the rejection hopper 11.

It is also apparent that when a coin having a diameter less than that of an acceptable coin is deposited in passageway 8 and since the feeler projection 23 is normally in its withdrawn position, it will pass through the space between projections 14 and 15 of the rocker, directly into the rejection hopper.

Having described our invention, we claim:

1. A coin separator comprising a frame, means

in said frame forming a coin passageway, a rocker pivotally positioned in said frame adjacent to said passageway, a pair of spaced abutments integral with said rocker projecting into said passageway, means for urging said rocker in normal rest position, crank shaped feeler means pivotally positioned on said rocker, said feeler means having a projection at one end adapted to movement into said passageway, means for urging said feeler to move said projection toward said passageway, cam means integral with said frame for normally holding said projection out of said passageway when said rocker is in its normal rest position whereby a coin descending in said passageway will straddle said abutments and rotate said rocker and be diverted thereby, and to simultaneously permit said feeler means to disengage its said projection from said cam means and to engage the end of the said projection with one face of the coin to retain thereon coins having holes therein.

2. A coin separator comprising a frame, gate means pivotally secured to said frame and normally forming a coin passageway between said frame and said gate means, a rocker pivotally positioned on said gate means adjacent to and outside of said passageway, a pair of spaced abutments integral with said rocker projecting through a clearance aperture in said gate means into said passageway, means for urging said rocker in normal rest position, crank shaped feeler means pivotally positioned on said rocker including a projection adapted for movement into said passageway, gravity means for urging said feeler in one direction for moving said projection into said passageway, cam means integral with said gate for normally holding said projection out of said passageway, a stripper lever pivotally secured to the outer surface of said gate having a tongue projecting into said aperture between said rocker abutments, a stop member integral with said frame for normally holding said stripper lever with its tongue out of said passageway, a spring means secured to said gate for urging said lever toward said passageway whereby a coin having a hole therein deposited in said passageway tested by said rocker and said feeler means and suspended by said projection in said passageway, will be stripped therefrom for descent and rejection in said passageway by the relative inward movement of said tongue when the said gate is moved outward from said frame.

3. In a coin separator means forming a coin passageway, a rocker pivotally positioned on said means outside of said passageway and having a pair of integrally spaced abutments projecting into said passageway, counterweight means integral with said rocker for urging said rocker to rest position, feeler means adjustably pivoted on said rocker including urging means therefor and an integral crank arm for entering a hole in a coin deposited on said abutments.

4. In a coin separator, means forming a coin passageway, a rocker pivotally positioned on said means and outside of said passageway having a pair of integrally spaced abutments projecting into said passageway for intercepting a coin of proper diameter, a crank shaped feeler means adjustably pivoted on said rocker, said feeler means having a crank arm for suspending thereon a coin having a hole therein, independent counterweight means integral with said rocker and said feeler means for normally urging said rocker in one position and normally urging said feeler means with said crank arm toward the face of a coin straddling said abutments, a fixed cam for holding said

feeler means out of contact with a coin suspended on said abutments when said rocker is in rest position whereby a coin of proper diameter and weight will move said rocker and permit the said feeler means to engage one face of said coin during its movement in said rocker and whereby a coin having a hole therein will be suspended on said crank arm.
